LEG-SUPPORTING MEANS FOR
OBSTETRICAL BEDS

Adrian Comper, Pittsfield, Mass., assignor to Hospital Appliances, Inc., Pittsfield, Mass., a corporation of Massachusetts

Application December 27, 1935, Serial No. 56,378

11 Claims. (Cl. 311—11)

The invention aims to provide a new and improved, unusually simple, rapidly and easily adjustable leg supporting means for use primarily upon beds designed for the delivery of infants, the construction being such that the legs of the prospective mother, regardless of her size, may be comfortably supported in any of the various positions which may be required, without any parts of the supporting means obstructing the necessary movements of the attending physician.

With the foregoing in view, the invention resides in the novel subject matter hereinafter described and claimed, description being accomplished by reference to the accompanying drawings.

Fig. 1 is a perspective view showing an obstetrical bed or table equipped with the invention.

Fig. 2 is a top plan view of one of the leg supports.

Fig. 3 is a side elevation of the support shown in Fig. 2.

Fig. 4 is a vertical transverse sectional view on line 4—4 of Fig. 3.

Fig. 5 is a horizontal sectional view on line 5—5 of Fig. 3.

Fig. 6 is a perspective view showing portions of the clamping and adjusting means for the saddle which underlies the knee.

Figs. 7, 8, and 9 are side elevations illustrating different positions of adjustment.

Fig. 10 is an end elevation partly in vertical section.

A preferred construction has been shown and will be specifically described, with the understanding however, that within the scope of the invention as claimed, variations may be made.

The invention is shown upon an obstetrical bed which includes a vertically adjustable and tilttable track frame 12, a frame 13 slidable along said track frame 12 and carrying a mattress section 14, and a drop frame 15 carrying another mattress section 16. Before the patient is moved to delivery position, the frame 13 and its mattress section 14 occupy a position toward the head of the bed, the frame 15 and mattress section 16 being then in a raised position at which they abut the frame 13 and mattress section 14. As the delivery time approaches, however, the frame 15 and mattress section 16 are lowered as seen in the drawings, and the frame 13 and its mattress section 14 are moved along the main frame 12 to the position shown. The improved leg supports are carried by the frame 13 and the patient's legs may be engaged with

said supports before dropping the frame 15 and sliding the frame 13 with the patient lying thereon, to the foot portion of the frame 12.

The corners of the frame 13 toward the foot of the bed, are provided with fixed vertical clamps 17 having hand levers or the like 18 by means of which they may be contracted or released. The vertical portions 19 of inverted L-shaped brackets 20 are received in the clamps 17 for rotative adjustment, the horizontal portions 21 of these brackets being provided with vertical clamps 22 having hand levers or the like 22' by means of which they may be contracted and released. Vertical rods 23 are received for vertical and rotative adjustment in the clamps 22, the upper ends of these rods being provided with horizontal bracket arms 24 integrally joined thereto, each of said bracket arms having a longitudinal slot 25.

Leg-supporting saddles 26 of longitudinally angular, transversely channel-shape form are disposed at the inner sides of the bracket arms 24, and two contacting plates 27 and 28 are interposed between each bracket arm and the adjacent saddle. The plates 27 contact with the inner sides of the bracket arms 24 and are provided with lugs 29 received in the slots 25. Each of the plates 27 is also provided with an opening 30 communicating with the slot 25 and with a series of teeth 31 spaced around said opening. Each plate 28 is rigidly secured by screws or the like 32 to a suitable boss 33 formed integrally with the adjacent saddle 26, and said plate is provided with an integral stud 34 passing through the opening 30. Plate 28 is provided also with teeth 35 engaging the teeth 31. Suitable clamping nuts 36, preferably having hand levers 37, are threaded upon the outer ends of the two studs 34 to engage the outer sides of the bracket arms 24. When these nuts 36 are tightened, the saddles 26 are tightly held in fixed relation with the bracket arms 24. When the nuts 36 are loosened however, the saddles may be adjusted longitudinally of the bracket arms 24 and may be tilted vertically about the axes of the studs 34.

To assist in rigidly connecting the plates 28 with the saddles 26, said plates may be provided with projections 38 embedded in the bosses 33. If desired, the studs 34 could well pass through openings in the plates 28 and be welded to said plates so that the inner ends of said studs would form the projections 38.

The lower sides of the saddles 26 are provided with integral apertured lugs 39 with which rods 40 are rotatably and slidably engaged, said lugs 55

being provided with set screws or the like 41 for holding said rods in adjusted position. These rods are adapted to underlie the lower portions of the patient's legs, and said rods are provided with 5 foot plates or stirrups 42 to comfortably engage the feet. These foot plates or stirrups are preferably permanently secured to the rods 40 and it will be seen that they may be adjusted in any required manner simply by loosening the set- 10 screws 41. These foot plates or stirrups, as well as the saddles 26 are preferably provided with slots 43 to receive suitable straps for securing the patient's feet and legs engaged with the supports.

15 By loosening the clamps 17 and swinging the brackets 20 so that the arms 21 project in the desired directions, the distance between the two saddles 26, may be varied as may be required, according to the size of the patient. By loosening 20 the clamps 22, the rods 23 may be vertically adjusted to dispose the patient's legs at the desired height, and said rods may also be turned about their own axes in said clamps 22 to dispose the saddles 26 either in parallel relation or in any 25 desired diverging relations. By loosening the nuts 36, the saddles 26 may be adjusted longitudinally of the bracket arms 24 or they may be tilted to any required positions. Any adjustments of these saddles 26, necessarily adjust the foot 30 plates or the like 42 which are mounted on said saddles by means of the rods 40, lugs 39 and screws 41. After once loosening these screws and adjusting the rods 40 according to the length of the patient's lower legs, said screws may be tightened 35 and the foot plates need no further adjustment with respect to the saddles.

Figures 8, 9, and 10 disclose three of the many ways in which the supporting means may be adjusted according to the requirements of the physician, the exigencies of the case, the ease of the patient, etc. In some cases, if desired, the brackets 20 may be removed and the rods 23 engaged directly with the clamps 17 or suitably secured to the bed itself. Also, the rods 40 with the foot 45 plates 42 may be detached from the saddles if required.

I claim:—

1. In a leg supporting means for an obstetrical or similar bed, two saddles shaped to underlie the 50 patient's knees, supporting and adjusting means mounting said saddles upon the bed, said supporting and adjusting means having portions for adjusting said saddles vertically, for adjusting said saddles longitudinally, and for tilting said 55 saddles about transverse horizontal axes; foot plates to engage the patient's feet, and means independent of said supporting and adjusting means and rigidly connecting said foot plates with said saddles for adjustment unitarily there- 60 with.

2. In a leg supporting means for an obstetrical or similar bed, two saddles shaped to underlie the patient's knees, supporting and adjusting means mounting said saddles upon the bed, said 65 supporting and adjusting means having portions for adjusting said saddles vertically, for adjusting said saddles longitudinally, for adjusting said saddles laterally into different spaced relations, and for tilting said saddles about transverse horizontal axes; foot plates to engage the patient's feet, and means independent of said supporting and adjusting means and rigidly connecting said foot plates with said saddles, for adjustment unitarily therewith.

75 3. In a leg supporting means for an obstetrical

or similar bed, two saddles shaped to underlie the patient's knees, supporting and adjusting means mounting said saddles upon the bed, said supporting and adjusting means having portions for adjusting said saddles vertically, for adjusting said 5 saddles longitudinally, for adjusting said saddles laterally into different spaced relations, for pivotally adjusting said saddles about vertical axes, and for tilting said saddles about transverse horizontal axes; foot plates to engage the patient's 10 feet, and means independent of said supporting and adjusting means and rigidly connecting said foot plates with said saddles, for adjustment unitarily therewith.

4. In a leg supporting means for a bed, one vertical clamp fixedly carried by the bed, an inverted L-shaped bracket having its vertical portion clamped for rotative adjustment in said one clamp, the horizontal portion of said inverted L-shaped bracket terminating in a second vertical 20 clamp, a vertical rod vertically and rotatively adjustable in said second clamp, the upper end of said rod being provided with an integral bracket arm projecting longitudinally from the foot of the bed, a leg support at one side of said bracket arm, and means adjustably mounting said leg support upon said bracket arm for movement longitudinally of said arm and for vertical tilting.

5. In a leg supporting means for a bed, one vertical clamp fixedly carried by the bed, an inverted L-shaped bracket having its vertical portion clamped for rotative adjustment in said one clamp, the horizontal portion of said inverted L-shaped bracket terminating in a second vertical 30 clamp, a vertical rod vertically and rotatively adjustable in said second clamp, the upper end of said rod being provided with an integral bracket arm projecting longitudinally from the foot of the bed, a saddle disposed at the inner side of said bracket arm and shaped to underlie the knee, 40 means adjustably mounting said saddle upon said bracket arm for movement longitudinally of said arm and for vertical tilting, a rod connected directly with said saddle and projecting therefrom in position to underlie the lower leg, 45 and a foot stirrup mounted on said rod.

6. In a leg supporting means for a bed, one vertical clamp fixedly carried by the bed, an inverted L-shaped bracket having its vertical portion clamped for rotative adjustment in said one 50 clamp, the horizontal portion of said inverted L-shaped bracket terminating in a second vertical clamp, a vertical rod vertically and rotatively adjustable in said second clamp, the upper end of said rod being provided with an integral bracket arm projecting longitudinally from the foot of the bed, a saddle disposed at the inner side of said bracket arm and shaped to underlie the knee, 55 means adjustably mounting said saddle upon said bracket arm for movement longitudinally of said arm and for vertical tilting, a rod to underlie the lower leg, means connecting this rod directly with said saddle for rotative and sliding adjustment, and a foot plate secured to and projecting upwardly from this rod in fixed relation therewith.

7. In a leg supporting means, a support, a saddle to underlie the knee, means adjustably mounting said saddle upon said support, a rod independent of said support and connected with 70 said saddle in position to lie at the back of the lower leg, and a foot plate mounted upon said rod.

8. In a leg supporting means, a support, a saddle mounted on said support to underlie the knee, the lower side of said saddle being pro- 75

vided with an apertured lug, a rod slidably and rotatively engaged with said lug and projecting longitudinally from said saddle to underlie the lower leg, means for securing said rod in adjusted 5 position in said lug, and a foot plate secured to and projecting upwardly from said rod.

9. In a leg supporting means, a fixed vertical clamp, an inverted L-shaped bracket having its vertical portion rotatively engaged with said 10 clamp, the horizontal portion of said inverted L-shaped bracket terminating in a second vertical clamp, a vertical rod rotatively and slidably engaged with said second vertical clamp, the upper end of said rod being provided with a 15 rigid bracket arm, a leg support at one side of said bracket arm, and means adjustably mounting said leg support upon said bracket arm.

10. In a leg supporting means, a bracket arm having a longitudinal slot, a plate lying against 20 one side of said bracket arm, said plate having an opening communicating with said slot and a lug received in said slot, the side of said plate opposite said bracket arm being provided with

teeth spaced around said opening, a leg support provided with a rigid stud extending through said opening and said slot, said leg support having teeth engaging the aforesaid teeth, and a clamping nut threaded on said stud and engaging the 5 side of said bracket arm opposite said plate.

11. In a leg supporting means, a bracket arm having a longitudinal slot, a plate lying against one side of said bracket arm, said plate having an opening communicating with said slot and a 10 lug received in said slot, the side of said plate opposite said bracket arm being provided with teeth spaced around said opening, a leg support, a second plate rigidly secured to said leg support and lying against the first mentioned 15 plate, said second plate being provided with a rigid stud passing through said opening and said slot, said second plate being provided also with teeth engaging the teeth of the first mentioned plate, and a clamping nut threaded on said stud 20 and engaging the side of said bracket arm opposite said plates.

ADRIAN COMPER.
